TROPHY BASE

Thomas F. Merle, Lincolnwood, Ill.

Application September 6, 1957, Serial No. 47,638

Term of patent 14 years

(Cl. D29—23)

Fig. 2 is a side elevational view looking from the left of Figure 1; and

Fig. 3 is a side elevational view looking from the right of Figure 1.

The back of the article is substantially plain.

I claim:

The ornamental design for a trophy base, as shown and described.
